UNITED STATES PATENT OFFICE.

FRIEDRICH KLUSMEYER, OF APLERBECK, GERMANY.

PORTABLE SPRAYER FOR DESTROYING VERMIN ON PLANTS.

Application filed April 29, 1924. Serial No. 709,938.

To all whom it may concern:

Be it known that I, FRIEDRICH KLUSMEYER, a German citizen, and residing at Aplerbeck, Westphalia, Germany, have invented certain new and useful Improvements in a Portable Sprayer for Destroying Vermin on Plants, of which the following is a specification.

This invention relates to an improved portable sprayer for destroying vermin on plants, which is represented on the accompanying drawing, in which Figs. 1 and 2 are respectively a rear view and a plan view of the same.

The steam boiler 1 with a furnace 2 is carried by axles 3 on wheels 4. Between boiler and wheels, said axles carry a feed water reservoir 5 in communication with said boiler on one side of the latter and a fuel tank 6 on the other side of said boiler. On the reservoir 5 a poison container 7 of transparent material, and on the tank 6 a receptacle 8 for storing large quantities of sulphur therein, are arranged. The boiler is fitted with a dome 9 in a way known in the art, a pipe 10 issuing from said dome and terminating in a rose. The pipe 10 has a ball joint 10^a and a branch 12 which is in communication with bye-pipes 13, 11 through which the poisonous matter can be sucked and conveyed to those places where the vermin are present.

According to the invention, a detachable knee-shaped receiver 14 serves for the evaporation of sulphur, it being for this purpose partly filled with sulphur from the storage receptacle 8 and then inserted with its lower member in the furnace 2 through a closable door 15. A bye-pipe 16 leads from said receiver 14 to the branch 12 of the pipe 10.

Shut-off cocks 17, 18 and 19 are inserted in the pipe 10 and bye-pipes 13 and 16 respectively, which can be opened or closed to suit requirements.

A steam nozzle 20 is preferably led from the boiler into the flue 21 to increase the action of the latter. A frame 22 serves to convey the apparatus on its wheels 4.

The steam generated in the boiler 1 passes through the dome 9 and escapes through the rose of pipe 10. By the suction effect of the outflowing steam, either with open cock 18 the poisonous matter in the container 7, or with open cock 19 the sulphur in the receiver 14, is caused to flow along the pipe 13, 55 or 16 respectively, and to escape with the steam through the rose pipe. As already mentioned, the knee-shaped receiver 14 is, for an evaporation of its contents, inserted with its lower member in the furnace 2. According to the kind of vermin to be destroyed, one or the other medium—either poison or sulphur—is employed separately.

What I claim, is:—

In a portable sprayer for destroying vermin on plants; the combination with a steam boiler having a furnace, a rose pipe issuing from the top of said steam boiler, and a poison container in communication with said rose pipe; of a separate detachable knee-shaped sulphur receiver inserted with its lower part in the furnace of said boiler and at its upper part in communication with said rose pipe, and shut-off cocks to connect either the poison container or the sulphur receiver with said rose pipe substantially as set forth.

In testimony whereof I have hereunto set my hand.

FRIEDRICH KLUSMEYER.
